SIDEBOARD

Warren Platner, 100 Mansfield Road, North Haven, Conn.

Filed Feb. 20, 1963, Ser. No. 73,653

Term of patent 14 years

(Cl. D33—13)

FIG. 1 is a front perspective view of a sideboard showing my design;

FIG. 2 is a rear elevation of the sideboard;

FIG. 3 is a side view of the sideboard;

FIG. 4 is a plan view of the sideboard; and

FIG. 5 is a sectional view on an enlarged scale taken in the plane indicated by the line 5—5 in FIG. 3, and showing a fragmentary portion of the vertical support member in greater detail.

I claim:

The ornamental design for a sideboard, substantially as shown.
